UNITED STATES PATENT OFFICE.

SARPALA MARTIN, OF ISHPEMING, MICHIGAN.

RAILWAY-TIE.

1,141,811.

Specification of Letters Patent.

Patented June 1, 1915.

Application filed November 27, 1914. Serial No. 874,282.

To all whom it may concern:

Be it known that I, SARPALA MARTIN, a subject of Russia, residing at Ishpeming, in the county of Marquette and State of Michigan, have invented new and useful Improvements in Railway-Ties, of which the following is a specification.

The present invention relates to improvements in ties for railway rails.

10 In carrying out my invention I propose to construct a metal tie which shall embody all the desirable features of a wooden tie and which shall be provided with means whereby rails may be easily, quickly and 15 efficiently secured to the tie without the employment of the ordinary spikes.

It is also my purpose to construct a tie of this character which will effectively connect the meeting ends of two rails without 20 the employment of fish plates or analogous securing devices.

With the above and other objects in view, the improvement resides in the construction, combination and arrangement of parts set 25 forth in the following specification and falling within the scope of the appended claims.

In the drawings: Figure 1 is a top plan view of the tie constructed in accordance with the present invention and showing two 30 rails secured upon the same, Fig. 2 is a side elevation of the same, the rails being in section, Fig. 3 is a longitudinal sectional view on the line 3—3 of Fig. 1, Fig. 4 is a transverse sectional view on the line 4—4 35 of Fig. 1, Fig. 5 is a similar sectional view on the line 5—5 of Fig. 1, Fig. 6 is a perspective view of the tie, the rail clamp and holding block being removed, Fig. 7 is a perspective view of one of the rail clamps, 40 Fig. 8 is a similar view of the holding or retaining block, and Fig. 9 is a plan view, parts being in section and illustrating the manner in which two rails may be connected and secured upon the tie.

45 Referring now to the drawings in detail, the numeral 1 designates my improved tie which is constructed of metal, preferably steel. The body 2 of the tie is of the desired proportions, and which is centrally 50 provided, upon its lower face, with a longitudinally extending rib 3. The tie adjacent its opposite ends is thickened for a considerable distance to provide flat rail seats

5, which are arranged flush with the remainder of the upper face of the tie, but 55 the ends of the said tie are provided with inwardly extending angular flanges 6, the underfaces of which agreeing in shape with the base flanges of the rails which they are adapted to receive, and the inner face or 60 wall of each of said lips is vertically straight and is of a height corresponding with the distance between the flange and the head of the rail so that the same will be received within the fishing spaces of the rail when 65 the rail is arranged upon the tie. The faces or walls are provided with the desired number of longitudinally extending pins 7 which are adapted to enter the bolt openings in the rails R. 70

The tie has its upper face channeled centrally and longitudinally from its rail seats 5, the central portion of the channel being widened, as indicated by the numeral 8 and the opposite or side walls provided thereby 75 are vertically straight, while the ends of the channel have their side walls inclined downwardly from their upper edges in outward directions, as indicated by the numerals 9. It will thus be noted that the restricted 80 channels provide substantially dove-tailed ways, the purpose of which arrangement will presently be described. The rail seats 5 may be, and preferably are, provided with upwardly extending studs 10, and these 85 studs are adapted to be received within vertical openings provided in the base flanges of the rails R.

Two rail clamps are employed, each indicated by the numeral 11, and each including 90 a body portion 12 which is of a width corresponding with the width of the tie proper and is provided with a head 13 having its inner face at its lower edge in cut or flanged, as at 14, to engage with the base flange of 95 the rail opposite that engaged by the flange 6 of the tie proper. The vertical end walls of the flanges 13 are adapted to be received within the fishing spaces of the rails and may be provided with openings to receive 100 the projecting ends of the pins 7, or when the said pins do not extend through the flanges of the rails, the said faces may be provided with pins, indicated by the dotted lines and which are adapted to be received 105 within the bolt openings not occupied by the

pins 7 of the tie. The lower face of the body 12 is horizontally straight, corresponding with that of the straight upper face of the tie, the body being of a width equaling 5 the width of the tie and the head being of a width equaling the enlarged or widened end 4 of the tie.

Formed centrally and extending longitudinally from the underface of the body 12 10 is a rib 15, the same being dove-tailed in cross section and being adapted to be received by the angular walls 9 provided in either of the end channels in the tie. The body, including the heads 13 of each of the 15 clamps is of a length corresponding with the length of the end channels, minus the thickness of the rails with which the said clamps engage, and it will be noted that the dove-tailed ribs 15 engaging with the dove-tailed 20 channels will prevent the vertical movement of the clamps.

The numeral 16 designates what may be termed the holding or wedge block. This block includes a head 17 which is of a 25 width equaling the width of the central portion of the tie and has formed upon its underface a longitudinally extending flange 18, the width of said flange corresponding with the distance between the vertical side 30 walls 8 provided by the central channel of the tie. The length of the holding block corresponds with the length of the central channel of the tie, and when the same is arranged within the said channel its opposite 35 ends will contact with the inner ends of the clamps 11. In order to secure the holding block in position upon the ties, the tie at the central portion thereof is provided with transverse openings 19 which are 40 adapted to register with similar openings 20 in the flange 18 of the member 16, bolts 21 passing through the registering openings and being secured by suitable nuts 22.

Preferably the ends of the blocks 16 are 45 provided with vertical slots 23 within which are adapted to be inserted wedge members 24 which contact with the end clamps and force the same into tight engagement with the rails.

50 In Fig. 9 of the drawings I have shown the device as employed not only as a tie but as a means for connecting the ends of two railway rails. The tie is of a construction similar to that previously described, except that the ends 4' are of a greater width 55 than the ends 4 of the tie 1. Also the head 13' and the flange 14' of the clamp 12' are of a width corresponding with the width of the head 4' and the flange 6'. In other 60 respects, as stated, the device is similar, but it will be noted that the added width of the flange and head permits of the joining of the meeting ends of two rails upon the tie. Furthermore, if desired, the walls of the 65 flanges of the tie as well as the walls of the

flanges of the clamp may be curved, so that the tie may be effectively employed upon the curves in a rail.

From the above description, taken in connection with the accompanying drawings, 70 the simplicity of the device, as well as the advantages thereof will, it is thought, be perfectly apparent to those skilled in the art to which such invention appertains without further detailed description. 75

Having thus described the invention, what I claim is:

1. In a metal tie, a body member having a central longitudinal rib upon its underface, the ends of the tie being formed with rail engaging flanges, the top of the tie having a longitudinally extending channel, the central portion of which being widened and having its opposite walls parallel and vertically straight, the reduced end extensions 85 of the channel having their walls beveled, clamps, said clamps each including a body having a head portion provided with a rail engaging flange, the underface of each of the bodies being formed with longitudinally 90 extending dove-tailed ribs adapted to engage with the angular walls of the end portions of the channel, a holding block including a head and having its underface provided with a central flange adapted to be received 95 within the central portion of the channel and to contact with the side walls thereof and with the opposite ends of the clamps, transversely arranged securing means for retaining the holding block within the channel 100 of the tie, and wedge members between the ends of the holding block and the end of the clamps.

2. A metal tie having its underface provided with a central longitudinally extending rib, its ends widened to provide rail seats and having rail engaging flanges which overlie the seats, the face of the tie between the seats being channeled longitudinally, the central portion of the channel being 110 widened and having vertically straight walls, while the reduced end portions of the channels have angular side walls providing dove-tailed recesses, the rail engaging flanges having longitudinally extending 115 pins, the rail seats having vertically projecting studs, rail clamps, said clamps having body portions of a width corresponding with that of the tie and head portions of a width corresponding with that of the 120 widened ends of the tie and of the rail engaging flanges thereof, said heads having their ends cut to provide rail engaging flanges, the body having its underface formed with a centrally arranged dove-tailed rib which is 125 adapted to be received within one of the end recesses of the channel of the tie, a holding block, said block including a head and a central flange, the opposite walls of which being vertically straight and adapted to be 130

received within the central portion of the channel, means passing transversely through the tie and flange for securing the holding block to the tie and its ends in contact with the ends of the clamps, and wedge members between the ends of the holding block and the ends of the clamps.

In testimony whereof I affix my signature in presence of two witnesses.

SARPALA MARTIN.
